US00D920344S

(12) **United States Design Patent** (10) Patent No.: **US D920,344 S**
(45) Date of Patent: **** May 25, 2021**

(54) **DISPLAY SCREEN WITH GRAPHICAL USER INTERFACE FOR A BASKETBALL PRACTICE DEVICE**

(71) Applicant: **Shoot-A-Way, Inc.**, Upper Sandusky, OH (US)

(72) Inventor: **John G. Joseph**, Upper Sandusky, OH (US)

(73) Assignee: **SHOOT-A-WAY, INC.**, Upper Sandusky, OH (US)

(**) Term: **15 Years**

(21) Appl. No.: **29/678,032**

(22) Filed: **Jan. 25, 2019**

(56)

(57) **CLAIM**

The ornamental design for a display screen with graphical user interface for a basketball practice device, as shown and described.

DESCRIPTION

The FIGURE is a front view of a display screen with graphical user interface for a basketball practice device. The broken lines are for illustrating environmental features and form no part of the claimed design.

1 Claim, 1 Drawing Sheet
